(57) **CLAIM**

The ornamental design for a front cover of a handset, as shown and described.

DESCRIPTION

FIG. 1 is a top plan view of a front cover of a handset showing our new design;

FIG. 2 is a right side view thereof;

FIG. 3 is a front view thereof;

FIG. 4 is a left side view thereof;

FIG. 5 is a bottom plan view thereof; and,

FIG. 6 is a perspective front view thereof.
